(57) **CLAIM**

The ornamental design for a cosmetic brush, as shown and described.

DESCRIPTION

[Continuation] This application is a reissue continuation application. This application is a continuation of U.S. Reissue application Ser. No. 29/554,344, filed on Feb. 10, 2016, which is a reissue of U.S. Design Pat. No. D699,041, issued on Feb. 11, 2014, which is a continuation of application Ser. No. 12/425,182, filed on Apr. 16, 2009, now abandoned.

FIG. 1 is a top perspective view of a cosmetic brush showing my new design [1];

FIG. 2 is a top view of a cosmetic brush showing my new design; and [2]

FIG. 3 is a first side view of a cosmetic brush showing my new design.

The ornamental design which is claimed is shown in solid lines in the drawings. The broken lines in the drawings are for illustrative purposes only and form no part of the claimed design.

1 Claim, 3 Drawing Sheets

Matter enclosed in heavy brackets [ ] appears in the original patent but forms no part of this reissue; matter printed in italics indicates the additions made by reissue.

Amended

Related U.S. Application Data

of Pat. No. Des. 699,041, which is a continuation of application No. 12/425,182, filed on Apr. 16, 2009, now abandoned.
